UNITED STATES PATENT OFFICE

FREDERICK ELWOOD STRUVE, OF PHILADELPHIA, PENNSYLVANIA

DESIGN FOR A STOCKING

Application filed August 29, 1931. Serial No. 40,957. Term of patent 3½ years.

To all whom it may concern:

Be it known that I, FREDERICK ELWOOD STRUVE, a citizen of the United States, residing at Philadelphia, in the county of Philadelphia and State of Pennsylvania, have invented a new, original, and ornamental Design for Stocking, of which the following is a specification, reference being had to the accompanying drawing, forming part thereof.

Figure 1 is a side elevation of the stocking. Figure 2 is a magnified showing of a por-

tion of the cuff of the stocking shown in Figure 1, the circular line indicating in a diagrammatic manner the circular edge of a magnifying glass.

The opposite side of the stocking is identical to that illustrated in Figure 1.

I claim:

The ornamental design for a stocking as shown and described.

FREDERICK ELWOOD STRUVE.
